UNITED STATES PATENT OFFICE.

LEON MANN, OF MOUNT VERNON, AND MORRIS KOPPELMAN, OF BROOKLYN, NEW YORK, ASSIGNORS TO HOLED TITE EGG PACKING CORPORATION, A CORPORATION OF DELAWARE.

CARTON FOR FRAGILE ARTICLES.

Application filed February 3, 1922. Serial No. 533,766.

To all whom it may concern:

Be it known that we, LEON MANN and MORRIS KOPPELMAN, citizens of the United States, and residents, respectively, of the county of Westchester, city of Mount Vernon, State of New York, and the borough of Brooklyn, in the county of Kings, city and State of New York, have invented certain new and useful Improvements in Cartons for Fragile Articles, of which the following is a specification.

The improvements relate primarily to containers for fragile articles, such as electric light bulbs, lamp chimneys, bottles, and similar fragile articles having a more or less globular form, but may be used for the purpose of enclosing and holding in suspension so as to protect against breakage or injury other articles as well, and also to protect anything that may be contained therein, in the case of electric light bulbs or other containers.

The objects of the improvements, amongst others, are to provide a safe, effective, and durable carton of the kind indicated, which will withstand all the ordinary shocks and strains to which such a container is subjected in transportation and handling and protect the article contained therein, and which can be made up and assembled at a small expense.

The present invention is in the nature of an improvement on the co-pending application of Morris Koppelman, filed October 24, 1921, Serial No. 509,904, to which reference may be had for the general construction.

The improvements are illustrated in the accompanying drawings, in which Figure 1 is a perspective of the carton embodying the improvements, with the lower part of the outer casing broken away at the bottom; Fig. 2 is a similar view of the same inverted; Fig. 3 is a vertical medial section of the carton with the parts in the position shown in Fig. 1, except that the top is closed; Fig. 4 is a plan of one of the diaphragms and its wings or flaps; Fig. 5 is a vertical section of the diaphragm shown in Fig. 4 on the line 5—5 of Fig. 4; Fig. 6 is a plan of the other diaphragm, and Fig. 7 is a vertical medial section thereof.

1 represents a rectangular box or container, which may be of any suitable sheet material. It has covers 2 and 3 at top and

bottom respectively, provided with flaps 4 55 adapted to be tucked inside the box 1 to hold the cover in position. The cover 2 is hinged at the rear edge of the top and the cover 3 at the front edge of the bottom, and the upper and lower side edges of the 60 box have flanges 5, with their ends converging inwardly, which are intended to be turned inwardly against the diaphragms 6 and 9 for holding the bulb or other article 65 against longitudinal movement. The parts 1 to 5 may be, and preferably are, made of a single piece of sheet material, such as straw board and the like, and are formed by punching or cutting out a flat sheet in manner similar to that illustrated in the 70 said co-pending application, and then folding the parts along definite lines to form the receptacle.

The diaphragms 6 and 9 are provided with central openings 10 and 11 respectively, 75 which may take any desired size or form, to fit and receive articles to be carried by the carton. In the present case, in which an incandescent electric light bulb is contained in the carton the openings are circular with 80 the opening 10 large enough to receive the bulb proper about midway between its lower extremity and its greatest diameter, and the opening 11 is small so as to receive and hold the butt. They are also provided 85 with teeth or fingers 12 and 13, respectively, which come in contact with the surfaces of the article contained in the carton and establish a spring grip and support for the same. The diameter of the openings however from the base of the fingers is less than the diameter of the portion of the article 90 inwardly of the diaphragm, so that the fingers may bend, if necessary, to a position substantially perpendicular to the diaphragm without permitting the article to slip through the opening. It will be understood that these fingers may be of any suitable form, the form herein shown being preferred.

The wings or flaps 7 and 8 of the diaphragms 6 and 9 are folded on lines parallel with the sides of the box and the diaphragms are made so as to fit snugly inside the box, and as these wings or flaps are hinged by being folded outwardly or toward the ends of the box they will have a constant tendency to spread out and press against the inner

walls thereof. This assists in holding the diaphragms in position and forms clamps to hold the flaps 4, when they are inserted between the said wings 7 and 8 and the inner wall. The primary object of the wings 7 and 8, however, is to form a support for the diaphragm, and the article received by its opening and to space and position them with respect to the ends of the box. The wings 10 therefore are varied in length to accommodate articles of different length.

The flaps 5 are also varied in length to correspond approximately to the length of the flaps 7 and 8, and are adapted to be 15 turned in until their inner edges press tightly against the diaphragms. The nature of the article contained and other circumstances will determine the exact length of these flaps 5 with respect to the wings of 20 the diaphragms and the position of the diaphragm, but the fact that they may be employed as a spring support to hold the diaphragms in place and exert a constant holding pressure thereon, and on the article supported by the diaphragms, gives them a very 25 useful function.

By means of the construction described and shown a carton is produced which may be employed to contain and hold in spring 30 suspension a great variety of articles, the cost of manufacture and the packing of the article therein being very small, and the suspension of the article being such that it and its contents are protected against all 35 ordinary shocks and strains.

It will of course be understood that the spacing of the article contained in the carton from the ends and side walls thereof may be varied to suit particular needs, and also 40 that a considerable degree of adjustment lengthwise may be obtained by trimming off the flaps 5, 7, and 8. It will also be apparent that either or both ends of the box may be cut down to shorten the carton, the flaps 45 5 in this case being folded if necessary instead of being cut off, and the covers 2 and 3 and the flaps 4 being folded inside their original folds.

In assembling the carton and placing an 50 article therein the covers are opened and the diaphragms forced in through its ends, so that the wings of the diaphragms are bent outwardly but maintain a pressure against the walls of the box. When one of the diaphragms has been thus positioned the article 55 may be inserted until one end or other portion is lodged in the openings of the diaphragm. The other diaphragm is then inserted until the edges of its opening are in 60 contact with the opposite end or other portion of the article. The carton is then closed by turning over its end covers and inserting their flaps between one of the wings of the diaphragm and the walls of the box, in each 65 case.

What we claim is:

1. A container for fragile articles, comprising a casing having flanges at its end turned inwardly into the interior thereof, and a diaphragm in said casing in contact with said inturned flanges and adapted to be held thereby against movement toward the end of the casing, said diaphragm provided with an opening for receiving a fragile article and holding it out of engagement with the side walls of the container, and the edge of the opening having numerous small tooth-like projections to provide article engaging projections. 70 75

2. In a container for fragile articles, a removable diaphragm adapted to be placed in the container in a position adjacent to but spaced from an end of the container, means for maintaining the diaphragm in said position, said diaphragm being provided with an opening forming a seat in which to receive the article, and the edges of the opening having a saw-tooth formation whereby to provide resilient article-engaging projections the length of the teeth of said formation being materially less than half the radius of the opening. 80 85 90

3. In a container for fragile articles, a removable diaphragm adapted to be placed in the container in a position adjacent to but spaced from an end of the container, wings on the margin of the diaphragm extending to the end of the container for holding the diaphragm away from the container end, said diaphragm being provided with an opening forming a seat in which to receive the article, and the edges of the opening having numerous small tooth-like projections whereby to provide resilient article-engaging projections. 95 100 105

4. A container for fragile articles, comprising a hollow box or body, diaphragms positioned therein having openings to receive a portion of the said article, the said diaphragms having flexible projecting members at the edges of said openings, and flap members carried by the end of the container for supporting the said diaphragms in position, said diaphragms also having members extending to the ends of the box. 110 115

5. A container for fragile articles, comprising a hollow box or body, diaphragms positioned therein having openings to receive a portion of the said article, the said diaphragms having flexible fingers at the edges of said openings, and means for supporting the said diaphragms in position, and said box having extending portions at its end of greater length than the distance between said ends and the diaphragm and adapted to be turned inwardly inside the box to press against said diaphragm. 120 125

6. In a container for fragile articles, a diaphragm positioned in the container and spaced from one end thereof, said diaphragm 130

being provided with an opening forming a seat in which to receive the article, said diaphragm having wing members extending to the adjacent end of the container, and flap members on the end of the container arranged to be turned inwardly into supporting engagement with the diaphragm being provided with openings forming seats in which to receive the opposite reduced end portions of the bulb, the edges of the openings having a toothed formation to provide resilient bulb engaging members, and flap members carried by the ends of the container and adapted to be turned inwardly into supporting engagement with said diaphragm, said flap members being longer than the distances between the diaphragms and the adjacent container ends whereby the flap members will assume a resilient curved formation when in diaphragm-engaging position. 20
7. In a container for fragile articles, a transverse diaphragm therein, provided with an opening for receiving a fragile article and holding it out of engagement with the end and side walls of the container, the said 25 diaphragm at the edge of the opening being provided with numerous small tooth-like projections, the points of which are adapted to come in contact with the article and, when the article is pressed against them, to exert 30 thereon a gripping influence.

Witness our hands this 20th day of January 1922, at the city of New York, in the county and State of New York.

LEON MANN.

MORRIS KOPPELMAN.
